RAILWAY TRACK LUBRICATING DEVICE

William F. Huck, Forest Hills, N. Y.

Application March 12, 1945, Serial No. 582,275

3 Claims. (Cl. 184—3)

1

The present invention, which is a continuation in part of my copending application, Serial No. 557,686, filed October 7, 1944, now abandoned, for improvements in railway track lubricating devices, relates broadly to improved means for applying lubricant to a rail head.

The principal object of the invention is the provision of means embodying a complete system for the efficient and dependable lubrication of rail heads over long periods of time.

Another and more particular object is to provide means for applying lubricant of high viscosity to the wearing surfaces of rails through the intermediary of means actuated by the wheels of passing trains, and having a design and construction especially adapted to withstand breakage and wear.

A further object is to provide means including inertia-operated pumping instrumentalities particularly adapted for applying lubricant of high viscosity to extensive lengths of rail surfaces efficiently and economically.

It is also an object of the invention to provide a railway track lubricating means of generally improved construction, whereby the construction will be simple, durable and inexpensive, as well as convenient, serviceable and efficient in use.

With the foregoing and other objects in view, which will appear as the description proceeds, the invention resides in the combination and arrangement of parts, and in the details of construction hereinafter described and claimed, it being understood that various changes in the precise embodiment of the invention herein disclosed may be made within the scope of what is claimed without departing from the spirit of the invention.

The present invention may be considered in some respects as an improvement over the device disclosed in my copending application, Serial No. 557,636, alluded to above. In the instant invention, it is preferred to provide an oil supply or storage tank in the vicinity of the railway track and sufficiently elevated to feed the lubricant to a level control valve which, in turn will feed the lubricant to and maintain a certain desired liquid or lubricant level in an inertia pump housing of the type mentioned in the aforesaid copending application, and also forming a component unit of the construction herein described and illustrated.

The invention will be best understood by reference to the drawings wherein:

Figure 1 is an elevational view, partly in section, of the device, as seen in the direction of the

2 railway track to which it is operatively applied;

Fig. 2 is an enlarged, fragmentary sectional view of the means employed for directly applying lubricant to the adjacent rail head;

5. Fig. 3 is a plan view of the device shown in Figure 1.

Fig. 4 is a side elevational view showing the flexible lubricating strips, depicted in Fig. 2, operatively engaged by the wheel of a passing

Fig. 5 is a fragmentary sectional view depicting a slightly modified form of the lubricant-apply ing means illustrated in Fig. 2, and showing same adjusted or tilted to effect an accumulation of lubricant against the rail head.

10 lubricant against the rail head.
Referring now to the drawings wherein similar characters of reference indicate corresponding parts in the several views of the preferred form of the invention, the numeral 11 designates a storage tank supported in any suitable manner, as by the standards 12 and straps 13, and containing a supply of lubricant 14. The lubricant 14 is preferably of a heavy type diluted with a suitable solvent, as described in my above-referred 20 to copending application No. 557,686, but any suitable lubricant may be employed.
25

The tank 11 is provided with a removable cover or filler plate 15, and a shut-off valve 16 to which is suitably coupled one end of a flexible conduit or hose 17 having its other end provided with a pipe fitting 18 secured to a float control valve, indicated generally at 19.

The control valve 19 comprises a housing 20 having a chamber 21 adapted to receive lubricant from the tank 11 via the hose 17. The chamber 21 encloses a hollow float member 22 normally supported by the lubricant within the housing 20 and which is received from the tank 11. The upper surface of the float 22 has an upwardly protruding valve stem 23 having a conical end 24 received in and adapted to close a conically shaped port or opening 25 formed in the top wall of the housing 20. The opening 25 directly communicates with a short passageway or channel 26 wherein the adjacent end of the pipe fitting 18 is secured. The control valve 19 is supported on a plate 27 having a flange 28 apertured to receive screw bolts 29 which are passed through a clamp member 30. Between the flange 28 and the clamp member 30, an upright 31 is slidably received whereby when nuts 32 on screw bolts 29 are loosened, it will be understood the control valve 19 may be raised or lowered to the height de-

Operatively connected to the chamber 21 of

the control valve 19 by hose 33 having pipe fittings 34, 35 is an inertia pump, indicated generally at 36 and having a structure and functions substantially as described in my copending application above-referred to. The inertia pump 36 has rigidly secured thereto a clamp bar 37 which, in turn, is fastened by screw bolts 38, 39; nuts 40, 41 and clamp plate 42, to the adjacent rail 43 anchored in the customary manner on the railroad ties 44.

Additionally secured to the rail 43 by the screw bolt 39 and nut 41, and adjustably retained in the position desired by a set screw 45 and lock nut 46, is an S-shaped bracket 47 adapted to support a lubricant-applying assembly indicated generally at 48 and hereinafter described in detail. The means for fastening the lubricating assembly 48 to the bracket 47 comprises a pair of bars 49, 50 between which the adjacent, extended end of the bracket 47 is clampingly secured by the screw bolt 51 that is protruded through horizontally-extending, resilient strips 52, 53. The strips 52, 53 are held in spaced relation by a member or strip 54 having slots or cut-out portions 55. Between the resilient strips 52, 53 a wick or strip of absorptive, flexible material 56, such as felt, is positioned. The wick 56 has its extended edge juxtaposed against the head 57 of the rail 43. The upper end of the screw bolt 51 is passed through a strip of sealing material 58 and is threadedly engaged with an adjacent portion of a lubricant-conducting pipe 59. It is to be understood that while only one S-shaped bracket 47 with coacting parts is described and illustrated, a plurality of these are provided in spaced relation along the length of the rail 43.

The conducting pipe 59 receives a supply of lubricant from the inertia pump in a manner similar to that described in my copending application Serial No. 557,686. In the present invention, a tube 60, provided with pipe fittings 61, 62 respectively engaged with the inertia pump 36 and the pipe 59, is adapted to convey lubricant from the said pump to the conducting pipe 59 to flow thence through holes 63 in this last named pipe and through coacting openings (not shown) in adjacent portions of the sealing strip 58 and upper resilient strip 52, into the slots 55 of the spacing member 54 which communicate with a pocket 64 formed between the lower surface of strip 52 and the upper surface of absorptive strip 56. By reason of the horizontal and comparatively close spacing of the strips 52, 56 and also strip 53, lubricant in the pocket 64 between these strips will have a tendency to accumulate therein, this tendency being aided by normal capillary attraction. Normally, the absorptive strip 56 is saturated with the lubricant in the pocket 64, a portion of this lubricant being transferred to the rail head 57 by the wiping action of the said strip 56 when moved downwardly by passing wheel flanges. From the pocket 64, the lubricant is extruded by pressure, as hereinafter described, into contact with the adjacent surface of the rail head 57 where the flange 65 of the wheel 66 in normal travel will engage it.

In the slightly modified form of the invention shown in Fig. 5, the lubricant-applying assembly 48 has been angularly adjusted or tilted by pressure of the adjusting set screw 45 against the S-shaped bracket 47. In the instant illustration, the absorptive strip 56, shown in Figs. 1 to 3 inclusive, has been omitted and upper strip 52 slightly shortened so that the lower strip 53 will extend beyond the said upper strip 52 and come

into contact with the rail head 57 when the set screw 45 has been turned, as mentioned above, to tilt the bracket 47. The shortening of the upper strip 52 and the tilting of bracket 47, it will be understood, permits lubricant in the pocket 64 between the two strips 52, 53 to overflow therefrom under the influence of gravity and into contact with the rail head 57 to form an accumulation 70 which is supported in sealing relation 10 against the said rail head by the lower strip 53.

The manner of operation of the device, in large measure indicated above, will now be briefly described:

From the main source of supply in the storage tank 11, lubricant will flow by gravity through valve 16, hose 17, pipe fitting 18, conical opening 25, into and filling the chamber 21 of control valve 19 until the stem 23 of float 22 enters and closes the said opening 25 against further ingress of lubricant, after the interior of the inertia pump 36 has been filled, via the hose 33, to a level corresponding to that of the aforesaid chamber 21 of the control valve 19, as best shown in Figure 1.

From the inertia pump 36, the manner of supplying lubricant to the rail head 57 is analogous in a number of respects to the method outlined in my copending application mentioned above. Reciprocation or motion of the rail 43 in a vertical plane under the weight of vehicle wheels passing thereover, will correspondingly reciprocate or oscillate the inertia pump 36 and the lubricating assembly 48, both of which are rigidly connected to the rail 43 through the intermediary of the clamp bar 37 and bracket 47 and the auxiliary coacting elements, as described hereinbefore. The oscillation or reciprocation of the inertia pump 36 will effect the ejection of a predetermined amount of lubricant into the pipe fitting 61 and thence through pipe 60 and pipe fitting 62 into the lubricant conducting pipe 59. Through the spaced holes 63 in the pipe 59 and coacting openings (not shown) in the strips 58, 52, the lubricant next flows into the slots or cut-out portions 55 of the spacing strip 54 and thence into the pocket 64 formed, as above-mentioned, between the strips 52 and 56.

As best shown in Figure 1, the resilient steel strip 52, when depressed by the flange 65 of a passing wheel 66 (shown fragmentarily), will function to extrude lubricant from the underlying space or pocket 64 and against the rail head 57, and simultaneously therewith, the margin or tip of the lubricant moistened absorptive member 56 will wipingly engage the adjacent surface of the said rail head in a continuously wave-like motion. This action will take place as each passing wheel successively and progressively engages the resilient strip 52. It will also be understood, as mentioned above, that capillary attraction between the lubricant and the horizontally and closely disposed strips 52, 53, either with or without the absorptive strip 56, will aid in maintaining an appreciable quantity of lubricant in readiness for release from the pocket 64 by the pressure of passing wheel flanges and for application to the rail head 57. While it is preferred to dispose absorptive material 56 between the two resilient strips 52, 53, it is to be understood that non-absorptive material may be employed without deranging the normal functioning of the lubricating assembly 48.

As described and illustrated, one pump 36 and one lubricating or applicator assembly 48 will suffice to lubricate the surface of the rail head

57 for a considerable extent, but it is to be understood that additional groups of lubricating assemblies 48 may be added and fed from the tank 11 and control valve 19, and that, if desired, additional inertia pumps 36 may supply a continuous length of lubricating assemblies.

It is to be understood that the invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the invention; and it will be further understood that each and every novel feature and combination present in or possessed by the mechanism herewith disclosed, forms a part of the invention included in this application.

Having thus described my invention, what I claim as new and desire to secure by Letters Patent is:

1. In a device for lubricating a rail, lubricant-applying means located adjacent to and contactable with said rail, said means including a plurality of resilient instrumentalities arranged to form a pocket, one of said instrumentalities being extended into proximity and contactable with said rail, lubricant-supplying means connected to an uppermost portion of the resilient instrumentalities and to the pocket; and a member connected to the rail and to the lubricant-applying means, said member being angularly movable, whereby the lubricant-applying means may be adjusted relatively to the rail.

2. In a device for lubricating a rail, lubricant-applying means arranged adjacent to and contactable with the rail, said means including a plurality of resilient instrumentalities arranged in spaced relation and providing a pocket, said

instrumentalities being flexible in a vertical plane, lubricant-conducting means connected to the resilient instrumentalities, other means for connecting the said pocket to the lubricant-conducting means, and additional means connected to the rail and to the resilient instrumentalities, said additional means including a plate and a threaded adjusting member, said member being engageable with said plate and effective to move it angularly with respect to the rail.

3. In a device for lubricating a rail, lubricant-applying means located adjacent to and contactable with the rail, said means including resilient instrumentalities arranged to form a pocket, one of said instrumentalities being longer than any other of the instrumentalities and having an end engageable with the rail, lubricant-supplying means connected to the resilient instrumentalities and to the pocket, a bracket connected to the rail, and screw means engageable with said bracket and effective to move it angularly.

WILLIAM F. HUCK.
